Primary Examiner — Karen E Eldridge Powers*Assistant Examiner* — Margaret Leah Bryan(57) **CLAIM**

The ornamental design for a nail dryer, as shown and described.

DESCRIPTION

FIG. 1 is a front, top, and left side perspective view of a nail dryer showing my new design.

FIG. 2 is a bottom, back, and right side perspective view of the nail dryer.

FIG. 3 is a front elevational view of the nail dryer.

FIG. 4 is a rear elevational view of the nail dryer.

FIG. 5 is a left side elevational view of the nail dryer.

FIG. 6 is a right side elevational view of the nail dryer.

FIG. 7 is a top plan view of the nail dryer.

FIG. 8 is a bottom plan view of the nail dryer; and,

FIG. 9 is an enlarged view of the nail dryer taken from the circle part in FIG. 2.

The broken lines depict portions of the nail dryer that form no part of the claimed design.
